FISHING PLUG

Rudolph Ross, Waverly, Tenn.

Application April 3, 1957, Serial No. 45,572

Term of patent 14 years

(Cl. D31—4)

Fig. 1.

Fig. 2.

Fig. 3.

Fig. 4.

Fig. 5.

Figure 1 is a side elevational view of a fishing plug, showing my new design;

Figure 2 is a top plan view thereof;

Figure 3 is a right end elevational view of Figure 1;

Figure 4 is an enlarged sectional view taken on the line 4—4 of Figure 2, the hooks being omitted for convenience of illustration; and

Figure 5 is an enlarged sectional view taken on the line 5—5 of Figure 2, the hook being omitted for convenience of illustration.

I claim:

The ornamental design for a fishing plug, as shown.
